WATCH BAND TERMINAL

Alfred Pinson, Stamford, Conn., assignor to Apex
Accessories Co., Inc., Greenwich, Conn.

Application October 17, 1950, Serial No. 190,458

4 Claims. (Cl. 24—241)

1

My invention relates to terminals for wrist bands of the type disclosed in Patent No. 2,557,683, June 19, 1951.

The object of the invention is to provide a terminal that will secure to a band a watch provided with rings or eyelets for attachment.

Another object of the invention is to provide terminals for wrist band ends, the construction of which terminals harmonizes with the wrist band of which they form a part. A further object of the invention is to provide a terminal that can be pre-assembled completely before attaching to the end of a band. This eliminates the necessity of stocking bands complete with terminals, as they can be attached to any type of band as disclosed in my application No. 99,931, filed June 18, 1949.

In the appended drawing forming part of this application,

Figure 1 is a bottom-up plan of the terminal with the slide moved to clear the pin, the attached band being outlined by dash and dot lines;

Figure 2 is a vertical section on line 2—2, Figure 1, with the pin swung to upright or open position;

Figure 3 is a similar section on line 3—3, Figure 1, the pin being shown in locked position;

Figure 4 is a transverse section on line 4—4, Figure 1, with the pin in the same position as in Figure 2;

Figure 5 shows a section similar to that of Figure 2 providing an additional feature not shown in Figures 1 to 4 inclusive;

Figure 6 is a plan of the inner face of the base plate; and

Figure 7 is a perspective view of the stud for the slide.

Referring to Figures 1 to 4 inclusive and Figure 6, the base plate 10 is formed of two spaced symmetrical longitudinal portions 11, the contours of which are similar to the contour of the liners used for the chain, for which the terminal is to be used. The two elongated portions 11 are bridged by a central part 13 co-planar with the portions 11 and disposed to one side of the transverse axis of the base plate 10 to provide a gap between the two portions 11 on the opposite side of the axis. The central part 13 is provided with an aperture 14 to engage a rivet for pivotally connecting the plate 10 to the central liner of a chain section shown in dash and dot lines in Figure 1.

Each of the elongated portions 11 has a lon-

2

gitudinally extending surface protuberance 15, semi-circular in cross-section and rising outward from the bottom face of the plate 10 and co-axial with the corresponding portion. Each of the portions 11 near the end farther removed from the portion 13 is slightly enlarged to form a spherical protuberance 16 merging with the longitudinal protuberance 15. One of the spherical protuberances 15 has a cut-out 17 through which passes a pin 18, the spherical head 19 of which pin bears in the protuberance 16. The cut-out 17 is directed towards the opposite portion 11 of the plate 10 so that the pin can span the gap between said portions 11 (see Figure 1).

15. The portion 11 at the protuberance 16 has a bendable lug 20 extending from the plate into the gap (see Figure 6), which lug is bent over after the head 19 is in the protuberance 16, as illustrated in Figures 1, 2 and 4, thus locking the pin within the protuberance 16, although permitting it to swing in the cut-out 17 to span the gap. It will be noted that the pin 18 swings on the outside of the base plate 10.

20. The protuberance 16 on the other portion 11 also has a cut-out 21 to receive the free end of the pin 18 when the same spans the gap. To

lock the pin in the position, as indicated in Figure 1, a slide 22 is mounted on the outside of the longitudinal protuberance 15 of the said portion 11, which receives the free end of the pin 18. The slide 22 is provided with a stud 23 (see Figures 3 and 7), which is secured to said slide so that the said stud prevents the slide from

35. rising from the plate while permitting it to slide on said protuberance 15 within the slot 24 provided therefor. A spring 25 is cradled in the protuberance 15 to move normally the slide across the cut-out 21 of protuberance 16 thereof and thereby prevent the pin from moving on its

40. pivot 19.

The contour of each longitudinal portion 11 is similar to the contour of the liner of the chain it is to fit, and in consequence it can be

45. equipped with the same type of covers 26 and with the same means of attachment 27 as provided for the chain. The height of the outward longitudinal protuberance 15 is substantially equal to the height of the network of the articulation parts provided under the liners of the band.

50. Since the pin 18 is normally disposed in close proximity of the wrist, the pin 18 cannot open even if the slide 22 is by accident cleared of the pin end, as shown in Figure 1, but, if desired, the pin 18 may be articulated by a helical spring

55.

28 (see Figure 5) cradled in the elongated protuberance 15 with one end of the spring anchored in an axial bore 29 in the head 19 of the pin 18', while the other end of the spring 28 is anchored after proper torsional tension to a lug 30 bent over as shown in Figure 6 and forming part of the base plate 10. The torsion of spring 28 may be made so as to maintain the pin normally in closed position, as indicated in Figure 1, or to maintain it in a normally upright position, as shown in Figure 4.

As shown in Figure 5, the helical spring 28 is torsioned to maintain the pin in an open position. This additional feature of the spring 28 further assures the improbability of the pin 18' being accidentally displaced from its locked position, for, if the torsional tension of the spring 28 is as shown in Figure 5, the tendency of the said spring is to turn the pin to open position, but in view of the fact that the slide 22 bars it, the torsional tension of spring 28 holds the pin tightly against the slide and, therefore, prevents the accidental displacement of said slide.

I claim:

1. A watch band terminal comprising a plate having a gap at one end, a pin pivotally connected to the plate to span the gap, a helical spring having its ends connected to the plate and pin respectively to turn the pin on its pivot by the torsional tension of the spring, said plate having means at the gap to receive the free end of the pin when the pin spans the gap, and a spring actuated slide to lock normally the free end of the pin to the plate.

2. A watch band terminal comprising a plate having a gap at one end, a pin pivoted to the plate to move across the gap, a helical spring anchored with one end to the plate and with the other end to the pin at the pivot thereof to turn the pin on its pivot across the gap under the torsional tension of the helical spring, said plate having means at the opposite edge of the gap to receive the free end of the pin when the same spans the gap, and a spring actuated slide on the face of the plate to lock normally the free end of the pin to the plate when the said pin engages the free end receiving means.

3. A watch band terminal comprising a plate defining two elongated members bridged by a middle portion disposed towards one end of the plate to provide a gap at the other end of said plate between said members, each of the said elongated members having a longitudinal cradle of semi-circular cross-section co-axial with the elongated member and accessible from the same side of the plate and bulging on the opposite side, a pin pivotally mounted near the end of a cradle

proximate to the gap and projecting through the cradle and adapted to span said gap on the side of the plate where the cradles bulge, a helical spring in the cradle where the pin is pivoted, said spring having one end thereof engaging the pin at the pivot, the other end of said spring being coupled to the plate, said spring being adapted to be torsionally tensioned to turn the pin across the gap, a slide mounted on the bulge side of the other cradle, and a spring in the cradle engaging the slide to move the same across the pin when said pin spans the gap to lock the pin to the plate, said middle portion having means for connecting it to a band link.

4. A watch band terminal comprising a plate defining a pair of spaced longitudinal members bridged by a co-planar portion disposed towards one end of the plate to provide a gap in the plate between said elongated members and the bridge portion at the opposite end, each of said elongated members having a longitudinal cradle of semi-circular cross-section co-axial with the elongated members and accessible from the same side of the plate, each cradle bulging on the opposite side of the plate, a pin having an enlarged end pivotally mounted near the end of a cradle proximate to the gap and projecting through the cradle and adapted to span said gap on the side of the plate where the cradles bulge, said plate having a tongue engaging the enlarged end of the pin to permit the pin to turn without moving longitudinally, a slide mounted on the bulge side of the other cradle, said cradle having a cut-out to receive the free end of the pin when same spans the gap, and a spring in the cradle engaging the slide to move the same across the cut-out to prevent the pin from moving on its pivot, said co-planar portion having means for connecting it to a band link.

ALFRED PINSON.
